JOHN E. PETERSON, OF IRVINGTON, NEW JERSEY, ASSIGNOR TO VAN VLAANDEREN MACHINE COMPANY, OF PATERSON, NEW JERSEY, A CORPORATION OF NEW JERSEY

REEL

Application filed May 6, 1930. Serial No. 450,214.

In the usual construction of reels used in dyeing there are a plurality of rimmed spiders and the spaced slats forming the periphery of the reel are secured to the spiders by screws, as by providing lateral flanges as the spider rims and entering screws from the inside of the flanges into the slats. The screws loosen and because they are of iron or steel to have the necessary strength they soon corrode under the action of the dye liquor, so that the slats become loose and the integrity of the entire reel structure is impaired. Besides, great care is required in boring the spider rims with the holes for the screws in order that in the completed reel the slats shall be equally spaced, and it is a tedious and laborious operation to assemble properly the slats of such reels as thus constructed.

I avoid these faults by providing the slat supporting rims of the reel with spaced projections between which the slats may be arranged and of which one at least in each pair forming a slat space has a retaining portion extending toward the other and of which one of them at least is bendable toward the other so as to bring said portion into retaining engagement with the interposed slat; in the preferred construction, the slats being as usual of impressionable material, as wood, the said retaining portions are more or less sharp tangs adapted to impress themselves into the slats. This makes possible an exceedingly strong reel structure whose parts may be readily and quickly assembled with the slats quite accurately spaced; also the ready removal of any slat when it becomes worn or damaged. Further, if the rim is of brass or other non-corrodible material and the projections are made integral therewith according to the best form there is the further advantage that loosening of the slats due to corrosion of their holding means will not occur.

In the drawings,

Fig. 1 is a perspective view of a reel embodying the invention;

Fig. 2 is an end elevation thereof; and

Fig. 3 is a fragmentary elevation of one of the spiders.

1 designates the reel shaft and 2 spiders secured thereon as by having their hubs split at 3 and provided with screws 4 for clamping the hubs to the shaft, all substantially as usual. The spiders are preferably formed of brass or equivalent non-corrodible material.

On the rim of each spider are projections 5. In the example these are arranged in a circumferential series in equally spaced pairs, with the projections in any one pair set apart 60 the same as those in any other pair so that any one of the slats, 6, which are all of the same width, will be adapted to be fitted to any one of the spaces. Each projection has a retaining portion, as a tang 7, projecting 65 toward the other.

The rims being thus formed, in order to assemble each slat with each spider rim it is only necessary to enter the slat into the space between the projections of a pair and thereupon cause one or each such projection to be bent toward the other so that the retaining portion 7 will engage the slat, in the present case by actually impressing itself into the slat which as usual is of yielding material, 75 as wood.

Having thus fully described my invention what I claim is:

1. A slat-supporting rim for a reel of the class described having a circumferentially 80 extending series of projections spaced from each other to receive between them the reel slats, one of the two projections forming each such space having a slat-retaining portion extending toward the other and one of said 85 projections being bendable toward the other to hold a slat interposed between them and cause said portion to retain the slat in said space.

2. In combination, a slat-supporting rim 90 for a reel of the class described and slats arranged in a circumferential series around the rim, the rim having a circumferentially extending series of spaced projections receiving the slats in the spaces between them, and 95 the projection at one side of each slat being bent toward the other and coacting therewith to hold the slat and one such projection having a slat retaining portion engaging the slat.

3. In combination, a slat-supporting rim 100

- for a reel of the class described and slats of yielding material arranged in a circumferential series around the rim, the rim having a circumferentially extending series of spaced projections receiving the slats in the spaces between them, and the projection at one side of each slat being bent toward the other and coacting therewith to hold the slat and one such projection having a slat retaining portion impressed in the slat.
4. A slat-supporting rim for a reel of the class described having a circumferentially extending series of integrally connected projections spaced from each other to receive between them the reel slats, one of the two projections forming each such space having a slat-retaining portion extending toward the other and one of said projections being bendable toward the other to hold a slat interposed between them and cause said portion to retain the slat in said space.
5. In combination, a slat-supporting rim for a reel of the class described and slats arranged in a circumferentially extending series around the rim, the rim having a circumferentially extending series of integrally connected spaced projections receiving the slats in the spaces between them, and the projection at one side of each such slat being bent toward the other and coacting therewith to hold the slat and one such projection having a slat retaining portion engaging the slat.
6. In combination, a slat-supporting rim for a reel of the class described and slats of yielding material arranged in a circumferentially extending series around the rim, the rim having a circumferentially extending series of integrally connected spaced projections receiving the slats in the spaces between them, and the projection at one side of each slat being bent toward the other and coacting therewith to hold the slat and one such projection having a slat retaining portion impressed in the slat.
- 45 In testimony whereof I affix my signature.
JOHN E. PETERSON.
